DESIGN FOR A TOY DUCK OR SIMILAR ARTICLE

Ludwig Leaf, Forest Hills, N. Y., assignor to Empire Plastic Corporation, New York, N. Y.

Application April 17, 1948, Serial No. 145,793

Term of patent 3½ years

(Cl. D34—2)

To all whom it may concern:

Be it known that I, Ludwig Leaf, a citizen of the United States, residing at Forest Hills, New York, in the county of Queens and State of New York, have invented a new, original, and ornamental Design for a Toy Duck or Similar Article, of which the following is a specification, reference being had to the accompanying drawing, forming part thereof, in which—

Fig. 1 is a plan view of a toy duck, illustrating my new design;

Fig. 2 is a side view of a toy duck illustrated in Fig. 1; and

Fig. 3 is a front view of the toy duck illustrated in Figs. 1 and 2.

I claim:

The ornamental design for a toy duck or similar article, substantially as shown.

LUDWIG LEAF.
